UNITED STATES PATENT OFFICE.

ADAM H. PRENZEL, OF HALIFAX, PENNSYLVANIA, ASSIGNEE TO UNITED SHOE MACHINERY COMPANY, OF PATERSON, NEW JERSEY, A CORPORATION OF NEW JERSEY.

PROCESS OF MAKING SHOES.

1,147,187.

Specification of Letters Patent. Patented July 20, 1915.

Application filed October 12, 1912. Serial No. 725,479.

To all whom it may concern:

Be it known that I, ADAM H. PRENZEL, a citizen of the United States, residing at Halifax, in the county of Dauphin and State of Pennsylvania, have invented certain Improvements in Processes of Making Shoes, of which the following description, in connection with the accompanying drawings, is a specification, like reference characters on the drawings indicating like parts in the several figures.

This invention relates to shoes and to processes of making shoes and is particularly applicable to the manufacture of stitch-down shoes.

In making stitch-down shoes which have a single sole and particularly in making stitch-down shoes by the improved process described in my co-pending application Serial No. 725,476, filed Oct. 12, 1912, which involves lasting the upper and securing it in lasted position by staples driven through the upper into the sole, I have found it advantageous to provide the sole with a shoulder to support the upper upon the inside of the shoe.

An object of this invention, therefore, is a process of making a shouldered sole, particularly adapted for use in stitch-down shoes, which will permit the production of such a sole, having the shoulder accurately positioned with respect to the edge of the sole, with a minimum waste of material.

Another object of the invention is so to form the shouldered sole that the material removed in the shouldering process may be utilized as a welt for the shoe of which the sole is to form a part.

Other objects and novel features of the invention will appear from the following description and claims when read in connection with the accompanying drawings.

In the accompanying drawings, Fig. 1 is a perspective view of a sole prepared by cementing together two like sole blanks; Fig. 2 is an exploded view showing the various parts which are separated from this sole in the step or steps of preparing a shouldered sole for a stitch-down shoe; Fig. 3 is a sectional detail showing the locations of these parts with respect to each other and the sole, and Fig. 4 is a perspective view of a shoe in which the sole and welt prepared by this process have been utilized.

In practising the process of this inven-

tion, I may start either with a solid sole of a thickness sufficient to provide the desired edge after the shouldering operation, or I may cement together two like sole blanks, as shown in Fig. 1. The more convenient practice is to build up the sole to the desired thickness by cementing together two like sole blanks. This procedure also facilitates the performance of the succeeding operations. When a sole made of two like sole blanks is employed, the upper blank 2 is preferably of a thickness equal to the height of the desired shoulder to be formed upon the completed sole, while the lower blank 4 is of the desired thickness of exposed sole edge. In cementing the blanks together, care is preferably taken not to extend the cement too near the edge of the blanks, since the operation of removing the welt to form the shoulder is facilitated if the welt is not cemented to the sole margin. Two blanks having been cemented together, as shown in Fig. 1, a cut 6 is made through the upper blank at the desired distance from the margin of the sole at which the shoulder is to be located, this cut being formed continuously about the sole. Preferably the cut is inclined somewhat to the upper face of the blank 2 so that the shoulder will be cut under somewhat in the finished sole. This facilitates securing a tight joint in the shoe. In order that the strip formed by the cut 6 may be utilized in making a welt and in order to facilitate the removal of this strip, a second cut 8 is also made through the upper blank 2, preferably simultaneously with the first cut. The distance between the cuts 6 and 8 is sufficient to provide for the accommodation of the upper and the lining of a shoe of which the sole and welt are to form a part. The strip 9 between the cuts 6 and 8 is waste material. The welt 10 which is left by the cutting operations already described is continuous and is of a size exactly to fit the shoe of which the shouldered sole is to form a part.

In making this shoe, it is preferable, in order that the edge of the sole may receive a proper finish, to cut the upper and lining somewhat back from the edge. In order that the welt when placed upon the out-turned flange of the upper may cover the cut-back edge of the upper, it is preferable that this welt be thicker at its outer edge than at its inner edge, so that its lower face

adjacent to its outer edge may contact with the upper face of the sole while the portion of the face adjacent to its inner edge rests upon the trimmed-back margin of the upper. To provide a welt of the desired cross-section a third cut 12 is made in the blank 2 of the sole, this cut being so inclined to the upper face of this blank that a skiving 14 is removed which is thicker upon its inner edge than upon its outer edge, thereby leaving a welt 10 of the desired cross-section.

It will be understood that the shoe is preferably made by the process of my co-pending application in so far as lasting the upper and securing it in lasted position is concerned, the upper being secured to the sole during the lasting operation preferably by staples inserted through the upper into the sole in the angle between the shoulder 20 and the sole margin.

Having described my invention, what I claim as new and desire to secure by Letters Patent of the United States is:—

1. That improvement in the art of making shoes which consists in separating from a sole a continuous strip shaped in cross-section to leave a shoulder upon said sole substantially flush with the edge of the last with which the sole is adapted to be used, placing said sole and an upper upon the last, turning out the lower margin of the upper, forming a continuous, unbroken welt from said strip, placing said welt upon said margin and uniting the welt, upper and sole 35 with stitches.

2. That improvement in the art of making shoes which consists in separating from a sole a continuous strip of a cross-section which will leave a shoulder upon said sole substantially flush with the edge of the last with which the sole is adapted to be used, removing from the inner edge of said strip a portion of substantially the thickness of the shoe upper and lining, placing said sole 40 and an upper upon the last, turning out the upper upon the projecting margin of the sole, placing said strip upon said margin and uniting the strip, upper and sole.

3. That improvement in the art of making shoes which consists in separating from a sole a continuous strip of a cross-section which will leave a shoulder upon said sole

substantially flush with the edge of the last with which the sole is adapted to be used, removing from the inner edge of said strip 55 a portion of substantially the thickness of the shoe upper and lining, removing from one face of said strip another portion shaped to leave said strip thicker upon its outside than upon its inside, placing said sole and 60 an upper upon the last, turning out the lower margin of said upper and securing it to the sole, trimming said margin back from the edge of the sole, placing said strip upon said margin and then uniting the strip, 65 upper and sole.

4. That improvement in the art of preparing soles for use in making stitch-down shoes which consists in cementing together two like sole blanks so that the edges are 70 flush, removing from one blank a continuous marginal strip of a width to leave the edge of said blank substantially flush with the edge of the last with which the sole is to be used and simultaneously removing 75 from the inner edge of said strip a portion of substantially the thickness of a shoe upper and lining whereby said strip may be utilized as a welt for the shoe of which said sole is to constitute a part.

5. That improvement in the art of making shoes which consists in cementing together two like sole blanks so that the edges are flush, removing from one blank a continuous marginal strip of a width to leave 85 the edge of said blank substantially flush with the edge of the last with which the sole is to be used and simultaneously removing from the inner edge of said strip a portion of substantially the thickness of a shoe upper and lining, placing said sole and the shoe upper upon the last, turning out the lower margin of said upper and securing it to the sole, placing said strip upon 90 said margin and then uniting the strip, 95 upper and sole.

In testimony whereof I have signed my name to this specification in the presence of two subscribing witnesses.

ADAM H. PRENZEL.
